CLAIM

The ornamental design for a trap cage cover, as shown and described.

DESCRIPTION

FIG. 1 is a front and top perspective view of a trap cage cover, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion indicated with numeric 9 in FIG. 1;

FIG. 10 is an enlarged view of a portion indicated with numeric 10 in FIG. 1;

FIG. 11 is an enlarged view of a portion indicated with numeric 11 in FIG. 1;

FIG. 12 is an enlarged view of a portion indicated with numeric 12 in FIG. 2;

FIG. 13 is an enlarged view of a portion indicated with numeric 13 in FIG. 2;
